JAMES W. BRUNDAGE, OF AKRON, OHIO, ASSIGNOR TO JOHN R. GAMMETER, OF AKRON, OHIO

METHOD AND APPARATUS FOR FILLING MOLDS

Application filed May 27, 1927. Serial No. 194,647.

This invention relates to methods and apparatus for filling molds such as rubber-heel molds, for example, with plastic material such as a rubber compound.

5 My chief objects are to provide for maintaining a continuous supply of stock in readiness for successive molds to be filled; to provide for applying a strong rolling pressure to stock within the mold cavities to compact it thoroughly therein; to provide for economy of power and of labor; and to provide more detailed advantages which will be manifest.

Of the accompanying drawings:

15 Fig. 1 is a vertical section of apparatus embodying and adapted to carry out my invention in its preferred form.

Fig. 2 is a section on line 2—2 of Fig. 1.

Referring to the drawings, the apparatus 20 in the preferred form here shown comprises a two-roll calender or rubber mill 10 adapted to form a sheet 11 of rubber stock from a bank 12 of the stock in the bight of an upper roll 13 and a lower roll 14 and to carry 25 the sheet upon the periphery of the lower roll.

Mounted under the rolls is a pair of horizontal supporting rails or brackets 15, 15, upon which are superposed a pair of wedge- 30 plates 16, 17 adapted to be adjusted, by set-screws such as the set-screws 18, 19 mounted in plates 23, 23^a secured to the framing, the set-screws bearing against the thicker ends 35 of the wedge plates. The wedge plates are adapted to raise or lower a guide-table 20 resting upon the upper wedge-plate and held against lateral movement by being fitted for sliding vertical movement between the end standards 22 of the calender and held against 40 longitudinal movement by the plates 23, 23^a.

The guide table is formed in its upper face with a guide-way for a mold-carrying slide 24 which is connected with the piston rod 25 of a fluid-pressure cylinder 26 which is 45 mounted upon the framing, for moving the mold-carrying slide 24 back and forth under the calender rolls to pass a succession of molds, such as the rubber-heel mold 27, under the lower calender roll 14 to be filled with 50 rubber stock therefrom. The mold-carrying

slide is provided with up-standing projections such as the flange 28 and the bar 29 for holding the mold in proper position thereon. The mold is formed with a plurality of mold-cavities 30, 30 separated by lands such as the 55 lands 31, 31, which preferably have their faces in the same plane.

To cause the sheet 11 of the rubber stock on the lower calender roll to bank up on the mold and to be forced into the cavities thereof, a roll-scraper 32 is slidably mounted in horizontal guide-ways such as the guide-way 33 formed in the inner faces of respective side flanges rising from the sides of the guide-table, the scraper being slidably held 60 in the guide-ways by rollers 34, 34 journaled between a pair of forks 34^a, having their stems slidably mounted in respective brackets mounted upon the calender frame, the forks being urged downward by compression 70 springs 34^b, interposed between the respective forks and brackets, and held against rotation by splines 34^c.

The scraper is formed with an upper beveled edge 35 adapted to scrape the stock 75 from the calender roll and with a lower beveled edge 36 adapted to fit against and wipe the stock into the cavities of the mold 27 as the latter passes under the roll, while the scraper's upper beveled edge 35 is in contact with the roll, the scraper being held 80 yieldingly but strongly wedged between the mold and the roll.

For holding the scraper in such operative position it is connected at its sides with a 85 pair of brackets such as the bracket 37 (Fig. 1) rising from the guide-table, by toggle links 38, 38, pivoted at 38^a, 38^a to brackets rising from the scraper, and by a pair of links such as the link 39, the two pairs of toggle links 90 being connected at their elbows by a cross-bar 40. The pivots 38^a preferably are at such height that when the scraper is in operative position, with the toggles nearly straightened, the pivots 38^a are approximately on a line between the bar 40 and the middle portion of 95 the scraper, so that the force of the toggle will not have a strong tendency to depress either end of the scraper with relation to the other.

The construction as described is such that the scraper, shoved by the toggle to its limit of movement imposed by its contact with the floors of the guideways 33 and with the calender roll 14, will be forced to a less advanced position by contact of a bevel 28^a formed on the leading margin of the mold, the rising face of the roll permitting the scraper to be lifted against the force of the springs 34^b, until the operative end of the scraper is sufficiently high for the leading end of the mold to pass under it, whereupon the springs 34^b, acting first through the adjacent roller 34 and later through both rollers 34, hold the scraper down flatly against the mold, in a horizontal position, notwithstanding difference in thickness of successive molds, while the mold passes through under the scraper, the toggles holding the scraper wedged between the roll and the mold.

The scraper 32 is preferably hollow and provided with flexible steam pipes 32^a, 32^b for keeping it hot so that it will operate without roughing the stock and to assist in keeping the stock warm as it is forced into the mold.

Upon the cross bar 40, between the toggles, is mounted a head 42 which is secured on the lower end of the piston rod 43 of a vertical fluid-pressure cylinder 44 having its upper end pivoted between a pair of brackets such as the bracket 45 projecting from the respective end standards of the calender.

Pivoted on a bar 41^a connecting stationary brackets such as the bracket 41^b is a mold-scraper 41 urged downwardly about the bar 41^a by hinge-springs such as the spring 41^c interposed between the scraper and the respective brackets 41^b, the bracket having formed thereon a stop 41^d adapted to be abutted by the hub of the scraper, to hold the scraper in position for rollers such as the roller 41^e journaled upon the scraper near the ends of its scraping edge to be engaged by respective studs such as the stud 28^b formed on the leading corners of the mold, so that the outer end of the scraper will be lifted for the passage of the leading end of the mold thereunder, notwithstanding difference in the thicknesses of successive molds, the hinge springs 41^c and the force of the stock against the inclined scraper then serving to hold the scraper down in proper scraping relation to the upper mold surface.

The two ends of the cylinder 44 are connected by respective fluid-supply and venting pipes 46, 47 with a four-way valve 48 mounted on the calender frame adjacent the path of the mold-carrying slide 27 and having an actuating lever 49 adapted to be engaged by a dog 51, mounted upon the mold slide in position to pass between the end of the calender roll 14 and the end standard of the calender, to retract the scraper 32 from the calender roll 14 when the slide has forced the mold

completely past the calender roll and the scraper 41.

The charging and venting pipe 52 of the front end of the slide-actuating cylinder 26, provided with a main valve 56, is also provided with a by-pass 53 having a fine-adjustment throttle valve 54 for throttling the venting of that end of the cylinder, to compel the mold-carrying slide to move forward at slow speed under the force of fluid supplied to the rear end of the cylinder through a charging and venting pipe 55, so that the mold will have a slower speed than the peripheral speed of the calender roll 14 and will thus cause a bank 57 of the stock to be maintained between the roll and the mold and will cause the stock to be wiped into the mold cavities by the roll as well as pressed therein by rolling pressure of the roll.

In the operation of the apparatus, the mold-carrying slide 24 with a mold 27 thereon being retracted to the right-hand limit of its movement as viewed in Fig. 1, the valve 48 is turned by hand to bring the scraper 32 to its operative position in which it is there shown. The main valve 56 of the pipe 52 is then closed and, the fine-adjustment throttle-valve 54 in the by-pass 53 being appropriately set, the rear end of the slide-actuating cylinder 26 is charged through the pipe 55.

In consequence of the throttling effect of the valve 54 the slide carries the mold 27 forward under the calender roll, and under and in contact with the scrapers 32 and 41, at a slower peripheral speed than that of the calender roll. Each scraper is lifted by contact of the mold and then comes into operation upon the upper face of the mold.

As the scraper 32 scrapes the stock from the calender roll the bank 57 is formed to a sufficient size by the time the mold arrives thereat, or the mold may be stopped with its leading end under the roll while the bank is enlarged. As the mold is moved farther the stock is compressed in the bight defined by the mold and the roll, so that stock of the bank is forced into the mold cavities in succession as the mold continues to move forward, and each mold cavity is progressively filled from the forward to the rear side thereof, the roll wiping the stock into the cavity, by reason of the roll's relatively fast speed, and also strongly pressing the stock in the cavity, by reason of the forward movement of the roll's surface and the mold and the convergence of their faces. A final pressing of the stock into the cavities is effected by the wiping action of the bevel face 36 of the scraper 32, and the lower face of the scraper prevents escape of stock from the forward side of the cavity until the cavity passes out of communication with the bank of stock.

The progressive filling of each mold cavity results in good expulsion of the air and the combined wiping action and roller-press-

ing action of the roll thoroughly compacts the stock in the cavity with comparatively little friction between the stock and its confining members and comparatively little internal friction in the stock, and consequently with economy of power consumption.

As the filled cavities pass the beveled edge 36 of the scraper 32 the stock within the cavity is sheared off from the bank 57 as well 10 as wiped into the cavities and as the mold passes the scraper 41 a final trimming of the upper faces of the cavity-occupying blanks and cleaning of the lands 31 is effected by that scraper.

15 As the mold-carrying slide closely approaches the left-hand limit of its movement as viewed in Fig. 1 the dog 51 engages the lever 49 of the valve 48 and causes the scraper 32 to be withdrawn horizontally from the calender roll 14, permitting the stock-bank 57 and the stock-sheet 11 to be carried on the roll back into the bank 12. When the mold reaches its limit of movement it is lifted from the slide and taken away for the vulcanization 25 therein of the blanks it contains.

The cylinder 26 is then reversed, returning the slide to its right hand limit of movement. The operation as described is then repeated for the filling of the next mold.

30 My invention thus provides numerous advantages, including those set out in the above statement of objects.

Modifications are possible within the scope of my invention as defined in the appended 35 claims.

I claim:

1. The method of filling the cavity of a mold with plastic material which comprises wiping the plastic vulcanizable material into 40 the cavity and confining it therein, and compacting the confined material by rolling pressure.

2. A method as defined in claim 1 in which the wiping and rolling pressure compacting 45 of the stock are effected concurrently.

3. The method of filling the cavity of a mold with plastic vulcanizable material which comprises forcing the stock into the cavity, confining and compacting it therein 50 by applying rolling pressure to the stock progressively across the mouth of the cavity, and removing excess stock by a shearing action directed across the mouth of the cavity, while maintaining the rolling pressure.

55 4. The method of filling the cavity of a mold with plastic vulcanizable material which comprises relatively moving a supply of stock across the mouth of the cavity and causing the stock to flow thereinto by a wiping of the outer region of the supply of stock in a direction toward the mold cavity and in a backward direction with respect to the supply's relative movement past the mold.

60 5. The method of filling the cavity of a mold with flowable material which comprises

flowing a mass of vulcanizable gum stock into the cavity by converging movement of the mold and a stock-pressing member with a mass of stock between them and confining the stock in the cavity without releasing the pressure imposed by said stock pressing member.

6. The method of filling the cavity of a mold with plastic material which comprises forming the material into a continuous sheet by passing it between rolls and impelling 70 stock of the sheet into the mold cavity while such stock remains integral with the continuous sheet and shearing off the stock while maintaining the impelling pressure.

7. The method of filling the cavity of a mold with plastic material which comprises holding the mold with the mouth of its cavity adjacent a sheet of stock carried upon the surface of a rotating roll and scraping the stock 75 from the roll into the cavity.

8. Molding apparatus comprising a cavitated mold and means for supplying plastic vulcanizable material under pressure to the cavity of the mold and for compacting it 80 therein by rolling pressure and means cooperating with said supplying means for wiping off excess material from the cavitated face of the mold while maintaining the pressure on the material.

9. Molding apparatus comprising a roll, a cavitated mold, means for so passing the mold relatively past the roll as to compact in the mold cavity a mass of stock between the two, and means cooperating with the roll and with 85 the mold for confining compact stock in the cavity, and for shearing excess stock from the mouth of the mold cavity in the passing of the mold.

10. Apparatus as defined in claim 9 in which the shearing means is so constructed 100 and arranged as to constitute a dam between the mold and the roll.

11. Molding apparatus comprising a cavitated mold, a member for pressing stock into the cavity of the mold, and means for effecting such converging movement of the two as to press into and confine within the cavity a mass of stock between them.

12. Molding apparatus comprising a roll adapted to carry a sheet of plastic stock on 115 its periphery, a cavitated mold, means for passing the mold relatively past the roll, and means for scraping stock from the roll into the mold and confining it therein.

13. Molding apparatus comprising a roll adapted to carry a sheet of plastic stock on its periphery, means for passing a mold relatively past the roll in position to receive stock therefrom into its cavity, a scraper, and means for holding the scraper in position as a 120 dam between the roll and the mold.

14. Apparatus as defined in claim 13 including yielding means for urging the scraper into scraping position with relation to the roll and means for so overcoming the same 130

yielding means as to force the scraping edge of the scraper circumferentially of the roll to permit the leading portion of the mold to pass the adjacent end of the scraper and then to release the said yielding means to hold the scraper wedged between the roll and the mold.

15. Molding apparatus comprising means for movably supporting a mold, means for moving the mold thereon, and means for pressing stock into the mold as the mold moves past the said pressing means, the means for moving the mold comprising a fluid-pressure cylinder, conduits for charging and venting the two ends of the cylinder and a fine-adjustment throttle-valve for regulating the venting of one end of said cylinder to regulate the speed of the mold's movement past the pressing means, one of the conduits being provided with a by-pass and with a valve within the span of the by-pass, and the throttle valve being mounted in the by-pass.

16. Molding apparatus comprising means for continuously feeding molds past a bank of plastic stock, and means including a roller to force some of the plastic stock into the mold cavities to confine the same therein said roller having a peripheral speed greater than the linear speed of the molds in their travel.

17. Molding apparatus comprising a rotary roll for feeding plastic stock, means for moving a mold tangentially past said roll at a linear speed less than the peripheral speed of the roll, and means mutually engaging the roll and the mold causing the stock to become banked therebetween whereby to fill the mold cavities by a combined wiping and pressing action.

40. In witness whereof I have hereunto set my hand this 25th day of May, 1927.

JAMES W. BRUNDAGE.
